(57) **CLAIM**

The ornamental design for an electrical connector, as shown and described.

DESCRIPTION

FIG. 1 is a front, top and right side perspective view of an electrical connector showing our new design;

FIG. 2 is a front elevational view of the electrical connector;

FIG. 3 is a rear elevational view of the electrical connector;

FIG. 4 is a left side elevational view of the electrical connector;

FIG. 5 is a right side elevational view of the electrical connector;

FIG. 6 is a top plan view of the electrical connector; and,

FIG. 7 is a bottom plan view of the electrical connector.

The broken lines in the drawings illustrate portions of the electrical connector that form no part of the claimed design.

1 Claim, 7 Drawing Sheets
